Primary Examiner — Abraham Bahta(74) *Attorney, Agent, or Firm* — Michael A. Springs(57) **CLAIM**

The ornamental design for a card with 2D barcode, as shown and described.

DESCRIPTION

FIG. 1 is a front view of one embodiment of the card with 2D barcode;

FIG. 2 is a front view of another embodiment of the card with 2D barcode;

FIG. 3 is a front view of another embodiment of the card with 2D barcode; and,

FIG. 4 is a front view of another embodiment of the card with 2D barcode.

The broken lines showing a card with 2D barcode are included for the purpose of illustrating portions of the "article" and form no part of the claimed design.

1 Claim, 4 Drawing SheetsFIG. 1

FIG. 2

FIG. 3

FIG. 4
